WALKING IRON FOR PLASTER CAST

Arthur L. Purcell, 15028 E. Root St., Baldwin Park, Calif.

Filed Mar. 26, 1956, Ser. No. 573,976

20 Claims. (Cl. 128—83.5)

My invention relates to improved therapeutic devices and more particularly to walking irons, a device which is applied to a cast on a fractured foot or leg to permit substantial use of the injured member during the healing period.

This application is a continuation in part of my co-pending application Serial No. 433,410, filed June 1, 1954 and now abandoned.

It is the general practice to treat fractures of the tibia, fibula, or both, as well as fractured metatarsal bones and related leg injuries by placing the injured member in a rigid cast. The cast is formed by wrapping a strip or strips of gauze impregnated with plaster of Paris, in which the plaster of Paris has been soaked in water, over a surgical stocking and/or rolled cotton worn by the patient. The cast is built up in this manner until it has the required size and strength to support the injured limb. After the cast has hardened it permits the patient to use the injured limb to a degree.

Such casts, however, are relatively fragile and do not lend themselves to repeated impact with the ground, such as would normally occur if the patient would attempt to walk directly on the cast. This difficulty has been heretofore overcome by incorporating in the cast, as an integral part thereof, a so-called walking iron or foot iron. This device ordinarily comprises a substantially U-shaped member; the sides or upright portions of the U being strapped securely to the cast with plaster of Paris tape and positioned so that the bight of the walking iron extends beyond the sole of the cast the required distance to prevent the cast from contacting the ground when the patient is walking. The wet wrappings that tape the walking iron to the cast must first be permitted to dry thoroughly before the cast can be used. After the tape has hardened, the position of the walking iron cannot be changed without splitting the cast and retaping the walking iron in a new position. Since the location of the ground contacting portion of the walking iron, with respect to the sole of the cast is very important, because it is essential that the bight be placed at the correct fulcrum point where the weight on the patient's foot is properly balanced to avoid discomfort, pain and possible injury, it is sometimes necessary to split the cast and relocate the walking iron several times before it is correctly positioned. There is no way for either the physician or patient to correctly determine the position of the ground contacting portion without actually walking on the iron after the cast has hardened sufficiently to support the weight of the patient; by this time it is too late to change the position of the iron with respect to the cast.

A purpose of this invention is to avoid the above difficulties by providing an improved form of walking iron that can be easily applied to a cast in the usual manner, and after the cast has hardened can be adjusted to the correct position whenever necessary, without interfering with the cast or hardened bindings that secure the walking iron to the cast, in any manner.

2

Another purpose of this invention is to provide an improved walking iron that can be easily applied to a cast and will support the sole of the cast off the ground at all times regardless of the positions normally assumed by the patient's foot during the process of walking.

A further purpose of my invention is to provide an improved walking iron of simple construction that can be positively and easily secured to the cast by interlocking it to the cast with the same material normally used in forming the remainder of the cast.

A related purpose of my invention is to provide a walking iron capable of angularly adjusting the position of the ground contacting member with respect to the sole of the cast and thus permit the patient's foot to assume a normal, walking position at all times.

I accomplish the above purposes by providing a substantially horizontally disposed member having cast engaging sole plates secured at or near the ends thereof. The horizontally disposed member is secured to a platform member which is provided with a ground engaging portion or element capable of placing the platform and horizontally disposed member the required distance above the ground thus preventing the cast and ends of the horizontally disposed member from contacting the ground when the patient is walking.

The objectives and purposes of my invention will be more clearly understood with reference to the following detailed description and accompanying illustrative drawings wherein:

Figure 1 is an isometric view of one form of the walking iron according to this invention.

Figure 2 is a bottom plan view of the device shown in Figure 1.

Figure 3 shows another construction of the walking iron indicating the manner in which a foot cast is mounted thereon.

Figure 4 is a bottom plan view of the device shown in Figure 3.

Figure 5 is a cross section view taken on the line 5—5 of Figure 2.

Figure 6 is a cross section view taken on the line 6—6 of Figure 4.

Figure 7 is a side plan view of an alternative construction of the device shown partly in cross section.

Figure 8 is a bottom plan view of the device of Figure 7.

Figure 9 is an end view of the device shown in Figure 7.

Referring to the drawings which are exemplary of preferred embodiments of my novel walking iron, there is included a substantially horizontally extending, cast engaging portion 10, mounted on a platform 11 that is secured or affixed to a ground engaging portion 12.

The cast engaging portion 10 shown in Figure 1 comprises a substantially horizontally disposed member 15 that may be of any desired length, cross section or construction. The horizontally disposed member shown in the drawings in preferably, as indicated, a rod of circular cross section, however, this member may have any other suitable cross section; it may be a splined rod, a rectangular or polygonal bar, or, if desirable it may comprise more than one rod, or may be a structural member such as an I-beam, channel, or other structural form.

At both end portions of the substantially horizontally disposed member there is mounted, as illustrated in Figs. 1 and 2, sole plate supports 16. These supports are provided with a longitudinal bore 17 extending the entire length of each support. The diameter of the bore is large enough to permit the end portions of horizontal member 15 to slide snugly therein. While the bore is shown in the drawings to be positioned symmetrically with respect to the longitudinal axis of the support mem-

ber, these bores may also be nonsymmetrically disposed if preferred.

A longitudinal slot 19 extends from one side of each sole plate support 16 to the bore 17. The symmetrical plane passing through the slots is preferably positioned to form a continuation of one of the horizontal radii of bore 17. A portion of the upper part of sole plate support 16 is preferably flat, forming a horizontal surface 29. This surface is provided with threaded holes 21 that extend from surface 20 a short distance into sole plate support 16. The lower portion of sole plate support 16 is also preferably provided with a flat surface 28 parallel to slot 19. A bore 29 having its axis perpendicular to the plane of slot 19 is located on surface 28 to permit it to extend from surface 28 through the portion of support 16 below slot 19, through slot 19 and into the upper portion of the sole plate support above the slot for a short distance. Portion 30 of bore 29 extending above slot 19 is threaded and the diameter of portion 31 of bore 29 below slot 19 is made large enough in diameter to permit free passage of the threads of a set screw 32. The portion of bore 29 adjoining the lower flat surface is preferably counterbored to receive the head of set screw 32. When the sole plate supports are in place on horizontal member 15 they may be clamped securely to it by simply tightening set screws 32.

A cast engaging sole plate 22 is provided with attaching holes 23 corresponding in position to holes 21 in sole plate support 16, to permit sole plates to be securely attached to the sole plate supports, preferably by means of flat headed screws 24. While the sole plates in Fig. 1 are shown as essentially triangular and provided with projections 25 extending from the perimeter of the triangular portion, the sole plates may be of any other desired shape or size, may employ any desired number of projections, may have the projections projecting in the opposite direction, may eliminate the projections entirely, or may be provided with holes if preferred. Sole plates 22 may also be secured to the supports by any other means such as soldering, welding, brazing, etc.

Platform member 11, shown in Figs. 1 and 2 is provided with a longitudinal bore 35 extending its entire length. The diameter of bore 35 is sufficient to permit substantially horizontally disposed member 15 to slide snugly therein. The overall length of platform 11, parallel to the axis of bore 35, is shorter than the distance between the inner edges of sole plate supports 16 when these are mounted on horizontally disposed member 15. This permits various longitudinal positions of the platform on horizontal member 15 as may be required.

The upper central portion 36 of platform member 11, above the horizontal diameter of bore 35, is preferably cut away as shown in Figs. 1 and 5, giving the platform member a roughly U-shaped longitudinal cross section with portions 37 extending vertically on either side of the cut out portion. Horizontally disposed slots 38 extend lengthwise in from one side of each vertical portion 37, parallel to the axis of bore 35, and continue until they intersect bore 35. The symmetrical horizontal plane passing through these slots lies preferably on the continuation of one of the horizontal radii of bore 35.

A bore having its axis perpendicular to the lower surface 40 of this platform 11 and positioned on the lower surface of the platform below each slot 38, extends from surface 40, through slot 38 and into the upper portion of upright member 37 a sufficient distance. That portion of bore 39 above each slot 38, is threaded, while the diameter of that portion of bore 39 below slot 38, is sufficiently large to permit passage of the threads of a set screw 41 that engage the threads above slot 38. The lower portion of bore 39 adjoining surface 40 is counterbored to house the enlarged head of set screw 41. When the platform member is mounted on hori-

zontally disposed member 15 and the set screws are tightened, the platform is securely clamped to the horizontal member. Also, if the horizontal member is round such as the rod shown in the drawings, the radial position of the sole plate supports can be varied independently or simultaneously with respect to the platform as desired.

A ground contacting base 12 is transversely secured to the lower surface 40 of platform 11, preferably in the center thereof, by suitable means such as bolts 43. 10 Ground contacting base 12 may also be an integral part of platform 11, or may be secured to it by welding, brazing, etc. The base 12 illustrated in Figs. 1 and 2, comprises a substantially rectangular member 44, preferably considerably longer than it is wide, to which there is fastened by a suitable means a semi-resilient, non-slip contact foot portion 45, made of rubber or similar material. The resilient foot may be attached to member 44 by bonding it to the member or by bolting it to member 44 with screws 46, inserted through holes 47 in resilient member 45. The lower portion of bores 47 are preferably counterbored to permit the heads of screws 46 from coming in contact with the ground. If desired a shim or shims 48 may be used to adjust the height of the base of the platform above the ground. It is to be understood that the base may also be any other desired shape or size, for example, elliptical, circular, etc.

An alternative design for a walking iron according to my invention is illustrated in Figs. 3 and 4. This embodiment employs a ground engaging base portion 12 that is similar in construction to the one shown in Figs. 1 and 2 without shims 48.

The platform member used in this alternative embodiment comprises a lower portion 50 having a semicircular groove 51 extending its entire length, preferably in the middle of the member. Holes 52 are provided at suitable positions, preferably at the corners of base 50. These holes 52 are perpendicular to the lower surface of the base 50. Base 50 is provided with a corresponding upper portion or cap 53 that is preferably coextensive with it and has a semicircular groove 54 extending its entire length and is positioned to correspond with groove 51. Grooves 51 and 54 are slightly less than semicircular in depth to permit gripping of the horizontal member. Cap 53 is provided with threaded holes 55 having their axes corresponding to the axes of holes 52; these holes being slightly smaller in diameter than holes 52. Cap 53 is secured to the lower portion 50 by a plurality of screws 57. The lower portions of holes 52 are preferably counterbored to receive the heads of set screws 57. When horizontal member 15 is laid in groove 51 and the corresponding groove 54 in cap 53 is placed over bar 15 and secured to the lower portion by screws 57, the substantially horizontal cast engaging assembly will be rigidly clamped to the platform.

In the embodiment shown in Figs. 3 and 4, sole plate supports are dispensed with and sole plates 58 are preferably permanently secured to bar 15, which in this embodiment is also a round rod, by welding sole plates 58 to the bar 15; these may be positioned at or near the ends of the bar as desired. Sole plates 58 may be of any required shape, may have notches cut into the sides thereof, may have cut out portions or they may be provided with openings. The plates shown in Figs. 3 and 4 are the preferred form and are rectangular, being longer than the are wide. The sole plates also have a slightly concave curve and are depressed slightly in the middle portion to permit the lower side of the depressed portion to contact the surface of rod 15 before the lower edge of the concave curve. It is understood that any other desired configuration for the sole plate may be used.

In some cases the patient will be more at ease if the sole plates attached to the horizontal member can be placed under the heel and ball of the foot. Figs. 7 and

8 show another embodiment of the invention which is particularly suitable for this purpose as well as for the ordinary uses to which a foot iron is put. In this construction a horizontal bar 60, also preferably circular in cross section is secured to a combined platform and ground contacting base 61. Bar 60 is preferably integral to the base 61 which extends transversely to the longitudinal axis of the horizontal bar and extends on either side thereof at a position preferably near the center of bar 60. A resilient foot portion 62, preferably of rubber, is secured to the bottom of base 61 by any desired method such as bolting, riveting, inserting the rubber foot in a retaining groove in base 61, etc. Base 61 extends a sufficient distance below bar 60 to support it the required distance above the ground.

A sole plate 63, preferably longer than wide, is secured to a sleeve 64 provided with a bore to permit horizontal bar 60 to slide snugly therein, the sole plate may also be an integral part of the sleeve and may have any other desired shape. The rectangular sole plates in Figs. 7, 8 and 9 are provided with openings 65. The sole plates are positioned preferably transversely at any desired position along sleeve 64; the preferred position being near the end of the sleeve. Sleeve 64 is provided with a threaded boss 66 whose axis is normal to the longitudinal axis of the sleeve. A sole plate and sleeve is slipped on each end of bar 60 and when properly located is locked to it by tightening screw 67 threaded in boss 66. The distance between the sole plates can be adjusted to fit the foot of the patient regardless of its length, and the fulcrum position of the ground contact can be adjusted after the cast has hardened.

The various embodiments are employed as follows: The sole plates are placed on bar 15 at the proper positions so as to make flat contact with the sole of the cast. The longitudinal axis of the horizontal member is generally placed directly below the centerline of the foot. The sole plates are taped to the cast by means of water soaked strips of plaster of Paris tape, or other binding tape suited for the purpose, until the sole plates are securely bound to the cast and cannot shift their position. The tape binding is permitted to dry and when the entire cast has hardened, the position of the ground engaging rubber foot 45, or 62 in Fig. 7, is adjusted by positioning ground engaging base 12 or the combined platform and ground engaging base 61 between the mounted sole plates until the patient can comfortably support his weight. The position of the fulcrum is fixed by tightening the set screws of the platform in Figs. 1 and 4, and those of sleeves 64 in Fig. 7. The foot irons shown in Figs. 1 and 7 permit independent radial positioning of the sole plate on horizontal bar 15 or 60 respectively. The angular relation of the ground engaging base to the sole of the cast is established by the patients normal walking position and can be adjusted while the patient is standing on the walking iron after the fulcrum has been properly located. When all screws have been tightened the position of the various elements of the foot iron will remain fixed until it is necessary to make further adjustments.

In some instances it may be desirable to bolt the sole plates to suitable inserts installed in the sole of the cast proper. In such a case the sole plates would be provided with suitable mounting holes adapted to receive large headed screws to engage the threads of the corresponding insert. Such an arrangement would eliminate the necessity of binding or taping the sole plates of the foot iron to the cast directly, however such inserts would have to be embedded in the sole portion of the cast at the time it is formed around the injured member.

The advantage of the various devices described herein over walking irons heretofore available lies in the fact that the walking iron can be taped at approximately the centerline and the position of the fulcrum can be shifted as often as necessary even though the bindings are hardened without injuring or disturbing any portion of

the cast. This feature saves the physician considerable time since the cast can be correctly supported after it has hardened and while the patient is standing on the foot iron, and it is not necessary to break the cast and reposition the foot iron as has been heretofore necessary when the bight of the foot iron was not in the proper place.

Another advantage is that the foot iron can be adjusted to the exact balance point whereas heretofore it was purely a hit or miss operation. The position of the foot iron balance can be changed as often as required should this become desirable at any stage of the healing process.

A feature of considerable importance is that the patient may alter or adjust the position of the balance point without requiring the services of the physician, until he locates the point at which the walking iron produces the least discomfort when his weight bears on the injured member. This avoids the necessity of visiting the doctor each time a minor adjustment is required.

20 1 claim:

1. An improved walking iron adapted to be attached to the underside of a foot cast, along the longitudinal axis thereof comprising: a substantially horizontally disposed member, said horizontally disposed member being circular in transverse cross-section; a platform secured to said substantially horizontally disposed member; a ground engaging portion secured to said platform, said platform and ground engaging portion being adapted to support the substantially horizontally disposed member above the ground; and a sole plate secured to said substantially horizontally disposed member on each side of said platform said sole plates being adapted to be attached to the sole of said foot cast, the position of said platform and ground engaging portion being adjustable between said sole plates.

2. An improved walking iron adapted to be attached to the underside of a foot cast, along the longitudinal axis thereof comprising: a substantially horizontally disposed member, said horizontally disposed member being circular in transverse cross-section; a platform secured to said substantially horizontally disposed member; a ground engaging member secured to said platform, said ground engaging member being positioned transversely to and extending on each side of the longitudinal axis of the horizontally disposed member, said ground engaging portion and platform being adapted to support the horizontally disposed member above the ground; and a sole plate secured to said horizontally disposed member on each side of the platform, said sole plates being adapted to be secured to the sole of the foot cast, the position of said platform and ground engaging portion being adjustable between said sole plates.

3. An improved walking iron adapted to be attached to the underside of a foot cast along the longitudinal axis thereof comprising: a substantially horizontally disposed member, said horizontally disposed member being circular in transverse cross-section; a platform secured to said substantially horizontally disposed member; a ground engaging portion secured to said platform, both said ground engaging portion and said platform being adapted to support the substantially horizontally disposed member above the ground; a sole plate slidably mounted on said substantially horizontally disposed member on each side of said platform and capable of axial movement thereon, each of said sole plates being provided with means for securing the sole plate at positions along the substantially horizontally disposed member said sole plates being adapted to be secured to the sole of a foot cast.

4. An improved walking iron adapted to be attached to the underside of a foot cast along the longitudinal axis thereof, comprising: a substantially horizontally disposed member below the underside of said foot cast; sole plates secured to said substantially horizontally disposed member adjacent the ends thereof said sole plates being adapted to be secured to the sole of a foot cast; a platform

slidably mounted on said substantially horizontally disposed member and capable of axial movement thereon, said platform provided with means for securing said platform at positions on said substantially horizontally disposed member between said sole plates; and a ground engaging base secured to said platform, said ground engaging base adapted to support the platform, substantially horizontally disposed member and sole plates above the ground.

5. An improved walking iron adapted to be attached to the underside of a foot cast according to claim 4 wherein said ground engaging base is provided with a semi-resilient foot portion that contacts the ground.

6. An improved walking iron adapted to be attached to the underside of a foot cast along the longitudinal axis thereof, comprising; a substantially horizontally disposed member below the underside of said foot cast; sole plates secured to said substantially horizontally disposed member adjacent the ends thereof said sole plates being adapted to be secured to the sole of a foot cast; a platform slidably mounted on said substantially horizontally disposed member and capable of axial movement thereon, said platform provided with means for securing said platform at positions on said substantially horizontally disposed member between said sole plates; and a ground engaging base secured to said platform substantially at the center thereof and extending transversely on either side of the longitudinal axis of said substantially horizontally disposed member when said platform is mounted thereon, whereby said platform, substantially horizontally disposed member, and sole plates are kept out of contact with the ground when said walking iron is in use.

7. An improved walking iron adapted to be attached to the underside of a foot cast according to claim 6, wherein the surface of said sole plates, that come in contact with the lower surface of said foot cast, is above the platform member when said sole plates are secured to said substantially horizontally disposed member and said substantially horizontally disposed member and platform are assembled.

8. An improved walking iron adapted to be attached to the underside of a foot cast along the longitudinal axis thereof, comprising: a substantially horizontally disposed member below the underside of said foot cast, said substantially horizontally disposed member being circular in cross section; sole plates secured to said substantially horizontally disposed member adjacent the ends thereof said sole plates being adapted to be secured to the sole of a foot cast; a platform slidably mounted on said substantially horizontally disposed member and capable of axial and radial movement thereon, said platform provided with means for securing said platform to said substantially horizontally disposed member at positions between said sole plates and at the required radial position with respect thereto; and a ground engaging base secured to said platform, whereby said substantially horizontally disposed member, sole plates and platform are kept out of contact with the ground when said walking iron is in use.

9. An improved walking iron adapted to be attached to the underside of a foot cast according to claim 8, wherein said platform comprises a lower member and a cap member, said lower member and cap member provided with corresponding longitudinally extending, substantially semicircular grooves corresponding to the outline of said substantially horizontally disposed member and are provided with means for clamping said lower and cap members to said substantially horizontally disposed member.

10. An improved walking iron according to claim 8, wherein the surface of said sole plates that comes in contact with the lower surface of said foot cast is above said platform member when said sole plates are secured to said substantially horizontally disposed member and

said substantially horizontally disposed member and platform are assembled.

11. An improved walking iron adapted to be attached to the underside of a foot cast along the longitudinal axis thereof, comprising: a substantially horizontally disposed member below the underside of said foot cast; sole plate supporting means mounted on said substantially horizontally disposed member adjacent the ends thereof, said sole plate supporting means being provided with clamping means to secure said sole plates supporting means to the substantially horizontally disposed member; sole plates secured to said sole plate supporting means said sole plates being adapted to be secured to the sole of a foot cast; a platform slidably mounted on said substantially horizontally disposed member and capable of axial movement thereon, said platform being provided with clamping means adapted to secure said platform to said substantially horizontally disposed member at positions between said sole plate supporting means; and a ground engaging base secured to said platform whereby said platform, substantially horizontally disposed member, sole plates and sole plate supporting means are kept out of contact with the ground when said walking iron is in use.

12. An improved walking iron adapted to be attached to the underside of a foot cast along the longitudinal axis thereof, comprising; a substantially horizontally disposed member below the underside of said cast, said substantially horizontally disposed member being circular in cross section; sole plate supporting means mounted on said substantially horizontally disposed member adjacent the ends thereof, said sole plate supporting means being provided with clamping means to secure said sole plate supporting means to said substantially horizontally disposed member; sole plates secured to said sole plate supporting means said sole plates being adapted to be secured to the sole of a foot cast; a platform slidably mounted on said substantially horizontally disposed member, said platform capable of axial and radial movement thereon and provided with clamping means to secure said platform to said substantially horizontally disposed member at positions between said sole plate supporting means; and a ground engaging base secured to said platform, whereby said platform, substantially horizontally disposed member, sole plates and sole plate supporting means are supported above the ground when said walking iron is in use.

13. An improved walking iron according to claim 12, in which said ground engaging base is secured to said platform substantially at the center thereof and extends transversely on each side of the longitudinal axis of the horizontally disposed member when said platform is mounted thereon.

14. An improved walking iron according to claim 12, wherein said sole plate supporting means are capable of independent radial adjustment on the substantially horizontally disposed member, thereby enabling the sole plates to contact the sole of said foot cast.

15. An improved walking iron adapted to be attached to the underside of a foot cast, along the longitudinal axis thereof, comprising: a substantially horizontally disposed member, said horizontally disposed member being circular in transverse cross-section; a platform secured to said substantially horizontally disposed member; a ground engaging portion secured to said platform, said ground engaging portion and said platform being adapted to support the substantially horizontally disposed member above the ground; a sole plate supporting means adapted to be slidably mounted on the substantially horizontally disposed member on each side of said platform and capable of axial movement thereon, each sole plate supporting means being provided with means for securing said sole plate supporting means at positions along the substantially horizontally disposed member; and a sole plate secured to said sole plate supporting

means, said sole plate adapted to be secured to the sole of said foot cast.

16. An improved walking iron according to claim 15, wherein the sole supporting means are in the form of a sleeve adapted to slide longitudinally on the horizontally disposed member. 5

17. An improved walking iron adapted to be attached to the underside of a foot cast, along the longitudinal axis thereof comprising: a substantially horizontally disposed member, said longitudinally disposed member being substantially circular in transverse cross-section; a ground engaging platform member secured to said horizontally disposed member, said ground engaging platform member being adapted to support the substantially horizontally disposed member above the ground; and a sole plate secured to said substantially horizontally disposed member on each side of said platform member, said sole plates being adapted to be attached to the sole of a plaster foot cast, the position of the platform member being adjustable between said sole plates. 10

18. An improved walking iron adapted to be attached to the underside of a foot cast along the longitudinal axis thereof, comprising: a substantially horizontally disposed member; a ground engaging platform member secured to the horizontally disposed member, said platform member being adapted to support the horizontally disposed member above the ground; a sole plate, adapted to be secured to the sole of a foot cast, slidably mounted on the horizontally disposed member on each side of the ground engaging platform member, each sole plate being capable of axial movement on said horizontally disposed member and turnable about the longitudinal axis thereof, said sole plates being provided with means for securing each sole plate to the horizontally disposed member when in position. 25

19. An improved walking iron adapted to be attached to the underside of a foot cast along the longitudinal

axis thereof, comprising: a substantially horizontally disposed member; a ground engaging platform member secured to the horizontally disposed member, said ground engaging platform member being positioned transversely to and extending on each side of the longitudinal axis of the horizontally disposed member, the platform member being adapted to support the horizontally disposed member above the ground; a sole plate adapted to be secured to the sole of a foot cast and slidably mounted on the horizontally disposed member on each side of the ground engaging platform member, each sole plate being capable of axial movement on said horizontally disposed member and turnable about the longitudinal axis thereof, said sole plates being provided with means for securing each sole plate independently to the horizontally disposed member when in position. 15

20. An improved walking iron adapted to be attached to the underside of a foot cast along the longitudinal axis thereof comprising: a substantially horizontally disposed member; a ground engaging platform member secured to said horizontally disposed member, said ground engaging platform member being adapted to support the substantially horizontally disposed member above the ground; a pair of sole plates, one of said sole plates being secured to said horizontally disposed member on one side of the ground engaging platform member and the other sole plate being secured to the horizontally disposed member on the other side of the ground engaging platform member, both of said sole plates being adapted to be attached to the sole of a plaster foot cast, the position of the platform member being adjustable between said sole plates. 25
